INTERMITTENT-FEELER MECHANISM FOR LOOMS.

Application filed March 30, 1926. Serial No. 98,518.

This invention relates to feeler mechanisms for looms, and more particularly to feeler mechanisms of the intermittent type wherein the feeler is held in an inoperative position for periods of time and is released at intervals to the performance of its feeling function.

Owing to the recurring contacts of the feeler with the filling on detecting beats where the feeler is mounted to engage the filling throughout the loom operation, much injury to the filling is liable to result. To avoid this condition, feeler mechanisms of the intermittent type have recently come into use, so that the feeler is normally held in a frontward inoperative position for periods of time and is released at intervals to permit it to move to feeling position, and should it detect a working supply of filling in the shuttle during its period of activity, it is again returned to a frontward inoperative position until, on a detecting beat, the feeler detects an approach to substantial exhaustion, whereupon it remains active and upon substantial exhaustion of the filling, calls for replenishment.

The feeler mechanism of the present invention is of this general type, but differs from previous intermittent feeler mechanisms in various features of structure and operation, as will later more fully appear.

In a prior application by the present applicants, Serial No. 45,349, filed July 22, 1925, a feeler mechanism is disclosed wherein the feeler is contained within an enclosing case with relation to which it has movements towards and from the front of the loom and also in a direction longitudinally of the shuttle. The feeler mechanism of the prior application has proven in practice to be sensitive both to the presence and absence of filling in the shuttle, and to act effectively in calling the change when the filling in the shuttle has become substantially exhausted.

The present invention is one aspect thereof and includes such a feeler combined with means for controlling its periods of activity and inactivity, and one of the objects of the present invention, therefore, is to provide an in-

termittent feeler mechanism of compact structure which may be readily applied to looms now in use and wherein the sensitivity of the feeler itself during its periods of activity is manifested as in the prior application hereinbefore mentioned. 55

In accordance with another feature of the present invention, the feeler and the intermittent control thereof are contained within casings and are consequently not subjected to the uncertain action that might result where the parts are exposed to the accumulation of lint ordinarily present in the weaving operation. The intermittent control mechanism is of novel construction and includes as part thereof a feeler catch for engaging the feeler when it is moved frontwardly on a detecting beat by a working supply of filling, and a feeler latch for moving the feeler frontwardly beyond the reach of the filling, and inasmuch as the parts are contained in casings, a differential device is employed for controlling the action of the latch and the trip which acts through the catch. 65

The invention, new combination of parts and novel features thereof will best be made clear from the following description and the accompanying drawings of one good form thereof.

In the drawings:

Fig. 1 is a perspective view of some of the loom parts at the feeler side thereof, provided with the present invention;

Fig. 2 is a plan view with the top casing of the intermittent control mechanism removed; 85

Fig. 3 is a section on the line 3—3 of Fig. 2;

Fig. 4 is a side elevation of the feeler mechanism with parts broken away, showing the relation of the elements thereof when the feeler is moved frontwardly by a working supply of filling on a detecting beat; 90

Fig. 5 is a view similar to that of Fig. 4, showing the feeler as having been moved frontwardly beyond the reach of the filling by the latch; 95

Fig. 6 is a plan view of the intermittent

control mechanism, showing the feeler in its retracted forward position;

Fig. 7 is a side elevation of the feeler mechanism with parts broken away, showing 5 the feeler as having been released to its period of activity;

Fig. 8 is a view in separated relation of the parts constituting portions of the feeler control mechanism;

10 Fig. 9 is a plan view showing more particularly the feeler and relation of parts when it detects substantial exhaustion of the filling in the shuttle; and

Fig. 10 is an enlarged perspective view 15 showing the rear end of the feeler.

The mechanism of the present invention is herein shown as associated with a train of devices for effecting replenishment of filling when the filling in the shuttle as been substantially exhausted, but since the details of 20 the replenishing mechanism form no essential part of the present invention, they are not herein shown and described.

The loom frame 1 may be of usual construction and as indicated in Fig. 1 an arm 2 rises from the transverse or usual rock shaft at the front of the loom and has pivoted thereto at 3 an actuator 4, the rear end portion of which is provided with a housing 5 containing an opening 6 into which may extend at times an operating member 7, herein shown as a part connected to the cam follower 8. Pivotaly mounted on the lugs 9 extending from the housing 5 is a lever 10 having an arm 11 which, under the control of the feeler to be hereinafter described, may be placed in the path of the operating member 7 to initiate replenishment of filling. Extending from the lever 10 in operative 40 relation therewith is a transmitter 12 which may be engaged and moved by the feeler when the latter partakes of its side swipe movement.

45 The lay has the usual shuttle box 13 for the reception of the shuttle 14, and the front wall of the shuttle box has an opening 15 adapted to register with a similar opening 16 in the front wall of the shuttle when the latter is properly boxed, the construction 50 being such that the feeler may enter the shuttle on detecting beats and detect the condition of the filling therein. The parts so far described with respect to the feeler mechanism may be substantially the same as those more fully shown and described in the prior application above mentioned.

Extending from the shipper stand 17 is an arm 18 to which may be adjustably connected the bracket 19 for supporting the intermittent feeler mechanism.

As more clearly indicated in Fig. 9, the feeler 20 is mounted for movement towards and from the front of the loom and longitudinally of the shuttle on the feeler stand 21 which is preferably formed as a casing hav-

ing a top plate 22 (Fig. 1) for enclosing the main portions of the feeler. The feeler enclosing casing is provided with trackways 23 (Fig. 9) on which the feeler may slide and tilt, and extending laterally from the 70 feeler is an arm 24, the toe portion 25 of which is adapted to engage a stop or projection 26 when the feeler is in its rearward feeling position, and about the projection 26 the feeler may swing laterally when it is 75 freed to its side slipping movement. A spring 27 is connected at one end to the laterally extending arm 24 at 28 and the rear end portion of the spring is engaged with a fixed portion 29 on the feeler stand. The 80 construction thus far described may be substantially the same as that more fully shown and described in the application hereinbefore mentioned. As indicated in Fig. 10, the feeler 20 has the toothed end portion 30, the 85 teeth of which are formed on the rounded end of the feeler to engage the filling, and when a working supply is present in the shuttle to effectively prevent side slipping 90 movement of the feeler on a detecting beat, but permit such side slipping movement when (as indicated in Fig. 9) the filling carrier or bobbin is substantially exhausted of filling.

Pivotaly supported at 31 in an opening 95 32 formed in the cover plate 22 is the feeler catch 33 having a shoulder 34, and the feeler catch 33 is normally under the influence of means, presently to be described, for holding the feeler catch in its feeler engaging position, as indicated in Figs. 3 and 4.

Associated with the feeler catch 33 is the feeler latch 35 pivoted on a stud 36 mounted on the cover plate 22. The feeler latch 35 extends over the tail portion 37 of the feeler catch and has a downwardly projecting lug 38 in close proximity to the shoulder 34 of the feeler catch. The feeler latch 35 is mounted not only for pivotal movement about its support 36 but is also capable of a lifting movement, so that when the feeler catch is moved into its feeler freeing position (as indicated in Fig. 7) the lug 38 of the feeler latch will likewise be lifted to thereby free the feeler to its period of activity. The feeler latch is under the influence of a spring 39 normally acting upon the latch to move the lug end portion 38 thereof rearwardly, and the spring 39 is utilized to normally press downwardly on the latch 35 and yet permit the latch to rise under the influence of the catch 33 when the latter is moved to its feeler freeing position (as indicated in Fig. 7). The function of the feeler catch is to engage the 115 feeler when it is moved forwardly by a working supply of filling in the shuttle on a detecting beat, and hold it for the engagement of the latch therewith, and, as will presently appear, the latch is thereupon 120

125 130

swung about its pivotal support to withdraw the feeler frontwardly beyond the reach of the filling under the dictates of the intermittent control mechanism.

5 As hereinbefore explained, the feeler 20 is under the influence of a spring at one side of its longitudinal axis to move the feeler into its rearward feeling position, and consequently the shoulder of the feeler catch 10 and the lug on the feeler latch are positioned to engage the laterally extending arm 24 of the feeler beyond the spring 27 at a point adjacent the toe 25 of the lateral projection, the result being that the feeler when held 15 in its forward inoperative position will be maintained in parallelism with its normal feeling position. This relation of the feeler catch and feeler latch with the laterally extending arm 24 of the feeler is important 20 because should the catch and latch engage the feeler between the spring and the longitudinal axis of the feeler, the tendency of the spring would be to turn the feeler laterally out of its true feeling position. 25 Extending upwardly from the cover plate 22 is a pin or bolt 40 which supports the intermittent control mechanism, and such pin or bolt 40 is utilized to maintain the cover plate 41 which encloses the intermittent control mechanism, and to this end the upper end of the bolt is threaded and provided with a nut 42.

30 Rotatably mounted upon the bolt or pin 40 is a toothed wheel 43, two of the teeth 35 of which (as at 44) are deeper than the remaining teeth. Also mounted on the pin or bolt 40 below the toothed wheel 43 for rotation on the bolt or pin is the toothed wheel 45, the teeth of which are spaced 40 apart similarly to the teeth of the wheel 43, and separating the two toothed wheels is the plate 46 which may be held from rotative movement by an arm 47 secured to the cover plate 22 by a pin 48.

45 The lower toothed wheel 45 has associated with it a trip to act upon the feeler catch at intervals, and also has a feeler latch withdrawing cam. These parts are probably best shown by Fig. 8 wherein the toothed 50 wheel 45 has secured to it the plate 49 from which extends a trip lug 50, and below the plate 49 the toothed wheel 45 has likewise secured to it the cam 51 for controlling the frontward and rearward position of the 55 feeler latch. In accordance with the present invention, the intermittent control mechanism is to be actuated step-by-step, first, to move the feeler latch frontwardly to withdraw the feeler with a quick movement beyond the reach of the filling, and, 60 second, to move the trip more slowly to permit longer periods of inactivity of the feeler before the trip acts upon the catch to free the feeler from the latch.

65 In the present instance of the invention, a

plunger operated pawl is employed to effect the desired movements of the feeler control mechanism, and the active end of the pawl is of sufficient width to act upon the teeth of both wheels at times, and to act only on the top wheel at other times, as will presently appear.

70 Mounted in bearings 52 rising from the cover plate 22 is a bunter 53 normally under the influence of a spring 54 tending to move the bunter rearwardly, and pivotally supported upon the bunter at 55 is the pawl 56 having a light spring 57 for normally moving the active end of the pawl into engagement with the toothed wheels. The bunter 75 53 has a sleeve portion 58 (Fig. 3) in which is mounted the yielding end 59 of the bunter, normally under the influence of a spring 60, the construction being such that when the end portion 61 of the sleeve meets the rear bearing 52 of the bunter, the yielding tip portion 59 of the bunter will yield frontwardly to accommodate the lay movement without at the same time giving to the pawl any more than its true active stroke. 80

85 Assuming that the feeler is held in its forward inoperative position (as indicated in Fig. 6) the pawl 56 will act upon the teeth of the upper wheel 43 and impart a step-by-step movement thereto, without at the same time engaging the teeth of the lower wheel 45, until a deep tooth 44 of the upper wheel comes opposite the pawl, whereupon the pawl will act upon both wheels 90 and impart the step movement, and since there are only two deep teeth on the upper wheel, the lower wheel will be given a step movement to actuate the trip 50 only twice during a full rotation of the upper toothed wheel, the effect being that the trip 50 will 95 be moved more slowly than is the upper toothed wheel and finally act upon the rear end portion of the catch 33, depress it, and disengage the catch and the latch from the feeler that the latter may move to full feeling position. 100

105 Assuming now that the feeler is in its full feeling position (as indicated in Figs. 2 and 3) and is moved frontwardly by a working supply of filling on a detecting beat (as indicated in Fig. 4), the shoulder 34 of the catch (which is now in the position indicated by Figs. 2, 3 and 4) will engage the laterally extending arm 24 of the feeler beyond the spring, and will hold it, and the feeler latch will thereupon be operated to swing it frontwardly and cause its downwardly extending lug 38 to withdraw the feeler frontwardly beyond the reach of the filling. To this end the feeler latch 35 has a projection 62 which rides upon the broken cam 51 and when the feeler has been released to its feeling function by the trip 50 (as indicated in Fig. 2) the projection 62 will 120 enter the broken portion or recess 63 of the 125

cam 51 and the feeler latch will assume its rearward position. When the feeler is to be withdrawn frontwardly by the latch, it is desirable that its frontward movement be impeded quickly, and to this end the teeth on the lower toothed wheel 45 substantially opposite the recess 63 of the cam are eccentrically arranged relative to the teeth of the lower wheel diametrically opposite, with the result that when the feeler has been moved frontwardly by a working supply of filling and has been engaged by the catch, a quick movement is imparted to the lower wheel during the action of the pawl upon the eccentrically arranged teeth opposite the recess 63.

In other words, the step-by-step movement imparted to the lower wheel 45 during the major part of its step-by-step movement is slow, and slower than the step-by-step movement imparted to the upper wheel, by reason of the non-engagement of the pawl with the teeth of the lower wheel until the deep teeth of the upper wheel come opposite the pawl, but when the latch is to be moved frontwardly to withdraw the feeler into a frontward inoperative position, and the projection 62 of the latch occupies the recess 63 of the lower wheel, the eccentric teeth on the lower wheel which are then opposite the pawl, will be engaged by the pawl and the lower wheel be given a quick step-by-step movement for part of a revolution to effect such quick withdrawal movement of the latch.

It will be noted that the latch overlies the tail end portion 37 of the catch, the result being that when the catch 33 is actuated by the trip 50, both it and the latch are raised to free the feeler.

From the construction described it will be apparent that the present invention provides a compact intermittent feeler mechanism, all of the parts of which are protected from the accumulation of lint which might interfere with the accurate operation of the feeler, and provision is made in the compact arrangement for prolonged dwells of the feeler during its inactive period, and the feeler itself when held in its frontward inoperative position is parallel to the position the feeler takes when in full feeling position.

A spring 64 may be interposed between the cover plate 41 and the intermittent control mechanism to maintain them in operative relation and prevent overthrow under the action of the pawl.

From the construction described it will be seen that when the feeler is moved frontwardly by a working supply of filling on a detecting beat, the laterally projecting arm 24 will be engaged by the feeler catch and be held by it in the position to which it has been moved by the working supply of filling.

Simultaneously the laterally projecting arm 66 will be engaged by the feeler latch, and when the feeler latch is given its quick frontward movement as the projection 62 rides over the inclined portion of the broken cam 51, it will withdraw the feeler further frontward, 70 away from the feeler catch and beyond the reach of the filling. Should the feeler detect a near approach to substantial exhaustion of filling on a detecting beat, it will not be moved sufficiently far frontward by the 75 partially denuded filling carrier for the feeler catch to engage the laterally extending arm 24 of the feeler and the feeler will consequently remain in feeling position and upon substantial exhaustion of filling it will 80 move longitudinally along the filling carrier and actuate filling replenishment or loom stoppage, as the case may be.

What is claimed is:

1. In an intermittent feeler mechanism 85 for looms, the combination of a feeler, a feeler catch to catch and hold the feeler when it is moved frontward by a working supply of filling, a feeler latch and operating means for withdrawing the feeler frontwardly away from the catch, step-by-step mechanism for moving the catch at intervals, interengaging parts between the catch and the latch for freeing the feeler from the latch when the catch is actuated by the 95 step-by-step mechanism.

2. In an intermittent feeler mechanism for looms, the combination of a feeler, means for withdrawing the feeler frontwardly beyond the reach of the filling, a 100 trip for freeing the feeler from said means at intervals, and a trip controller comprising two independently rotatable wheels, a bunter actuated pawl operative on one of said wheels on each active stroke of the 105 pawl, means carried by said operated wheel for controlling the action of the pawl on the other wheel, and connections between the said other wheel and trip for releasing the feeler when the pawl has moved said other wheel a predetermined amount.

3. In an intermittent feeler mechanism for looms, the combination of a feeler, a feeler latch for holding the feeler in a frontward inoperative position, a toothed wheel having a trip for freeing the feeler from the latch, a bunter actuated pawl for turning said toothed wheel, and means for rendering the pawl active upon said toothed wheel at irregular intervals during the regular bunter actuation of said pawl.

4. In an intermittent feeler mechanism for looms, the combination of a feeler, a feeler latch for holding the feeler in a frontward inoperative position, a toothed wheel having a trip for freeing the feeler from the latch, a bunter actuated pawl for turning the toothed wheel, and a second wheel

having deep and shallow teeth for rendering the pawl active and inactive at intervals on the said toothed wheel.

5. In an intermittent feeler mechanism for looms, the combination of a feeler, a feeler latch for holding the feeler in a frontward inoperative position, a trip for freeing the feeler at intervals, a toothed wheel carrying said trip, a step-by-step pawl for 10 actuating said toothed wheel, and a pawl controller operated by the pawl for rendering the pawl operative at intervals on the said toothed wheel.

6. In a feeler mechanism for looms, the 15 combination of a feeler, a latch for retracting and holding the feeler in a frontward inoperative position, a step-by-step device having a track for retracting the latch and a trip for freeing the feeler at intervals, a 20 pawl for operating said device, and a pawl controller for rendering the pawl operative on said device during some of its active strokes and inoperative on said device during others of its active strokes.

25 7. In a feeler mechanism for looms, the combination of a feeler, a latch for withdrawing and holding the feeler in a frontward inoperative position, a toothed wheel having a track for withdrawing the latch 30 and a trip for freeing the feeler, a second toothed wheel having teeth of different depths, a bunter having a pawl to act upon both toothed wheels and controlled in its operative relation with the first toothed wheel 35 by the variation in depths of the teeth on the second toothed wheel.

8. In a feeler mechanism for looms, the combination of a feeler stand, a floating side-slipping non-pivoted feeler mounted directly on the stand for movement towards and from the front of the loom and in a direction longitudinally of the shuttle, a spring acting upon the floating feeler to move it to rearward feeling position, a latch 40 for holding the floating feeler in a frontward inoperative position, and means for tripping the latch at intervals that the floating feeler may have periods of activity and inactivity during weaving with the same 45 supply of filling in the shuttle.

50 9. In a feeler mechanism for looms, the combination of a feeler stand, a floating side-slipping, non-pivoted feeler mounted directly on the stand for movement towards and from the front of the loom and in a direction longitudinally of the shuttle, an arm extended laterally from the floating feeler, a spring acting to move the feeler to its rearward feeling position, a latch 55 adapted to engage the laterally extended arm to hold the floating feeler in a frontward inoperative position, and means for freeing the feeler from the latch at intervals that the floating feeler may have periods of activity and inactivity during 60

weaving with the same supply of filling in the shuttle.

10. In a feeler mechanism for looms, the combination of a feeler stand, a floating side-slipping and non-pivoted feeler directly mounted on the stand for movement towards and from the loom and in a direction longitudinally of the shuttle, a lateral projection extending a substantial distance from the feeler, a spring acting upon the lateral projection at one side of the longitudinal axis of the feeler to move it rearwardly into feeling position, a latch for engaging the lateral projection to hold the feeler in a frontward inoperative position parallel to its rearward feeling position, means for moving the latch frontwardly when engaged with the lateral projection to withdraw the feeler beyond the reach of the filling, and a trip to disengage the latch at intervals that the feeler may move to feeling position. 70 75 80 85

11. In a feeler mechanism for looms, the combination of a feeler having periods of activity and inactivity during weaving with the same supply of filling in the shuttle, a feeler control mechanism comprising a catch for engaging the feeler when it is moved frontwardly by a working supply of filling, a latch for withdrawing the feeler frontwardly away from the catch, a trip for freeing the feeler at intervals, and an enclosing case for protecting the feeler control mechanism from accumulation of lint and foreign substances. 90 95 100

12. In a feeler mechanism for looms, the combination of a feeler stand comprising an enclosing case, a floating side slipping non-pivoted feeler mounted directly within the enclosing case for movement towards and from the front of the loom and in a direction longitudinally of the shuttle, intermittent control mechanism for holding the feeler in a frontward inoperative position during its periods of inactivity mounted above the feeler enclosing case, and an enclosing case for protecting the intermittent control mechanism that the floating feeler and control mechanism may both be protected and the floating feeler be freed at 105 110 115 intervals during weaving with the same supply of filling in the shuttle.

13. In a feeler mechanism for looms, the combination of a feeler having a laterally extending arm, a spring acting upon said arm to normally move the feeler rearwardly, an enclosing case for said parts, means mounted above the case and projecting into the case for engaging the laterally extending arm of the feeler to hold it in frontward inoperative position, and intermittent control mechanism mounted above the case for controlling said means. 120 125

14. In a feeler mechanism for looms, the combination of a feeler having a laterally 130

extending arm, a spring acting upon said arm to normally move the feeler rearwardly, an enclosing case for said parts, means mounted above the case and projecting into the case for engaging the laterally extending arm of the feeler to hold it in frontward inoperative position, intermittent control mechanism mounted above the case for

controlling said means, and an enclosing case for protecting said means and control mechanism.

In testimony whereof, we have signed our names to this specification.

LARKIN H. BROWN.
GEORGE E. REPASS.
